UNITED STATES PATENT OFFICE

ISIDOR LEVITON, OF BROOKLYN, NEW YORK, ASSIGNOR TO LEVITON MANUFACTURING COMPANY, OF BROOKLYN, NEW YORK, A CORPORATION OF NEW YORK

ELECTRIC-LIGHT FIXTURE

Application filed March 7, 1928. Serial No. 259,721.

This invention relates to an adjustable support for electric light socket that is made in such a manner that the socket can be turned through a wide angle in a fixed plane. The support is made of a somewhat U-shape and is provided with arms that may be pivoted on a rod or bolt, and is attached to the cap of an electric light socket in a convenient and permanent manner.

The invention will be understood from the description in connection with the accompanying drawings in which Fig. 1 is a side elevation of an illustrated embodiment of the invention; Fig. 2 is a section through the line 2—2 of Fig. 1; and Fig. 3 is a plan view of the support. In the drawings reference character 1 indicates the shell of an electric light socket of the well known sort and the cap therefor is indicated by the reference character 2. The flat upper portion of the cap 2 is provided with the usual opening 3 and a bracket or support is connected in this opening. The bracket or support comprises a disc-shaped portion 4 and parallel arms 5 attached to the disc-shaped portion. Holes or openings 6 are provided near the outer ends of the arms 5 for pivoting the support on a bolt or rod or the like. Provision is preferably made for clamping the bracket arms to hold them in the adjusted positions, or the support may be frictionally pivoted so as to remain in the position to which it is turned.

The disc like portion 4 of the support is attached to the cap 2 by pressing the central portion of the metal inwardly leaving a hole 7 and forming a cylindrical extension that projects through the hole 3 in the cap 2. The end of the cylindrical extension is pressed outwardly or riveted along the lower side of the flat portion of the cap 2 as indicated at 8 so as to hold the same securely in position.

The electric wires can be threaded through the hole 7 and connected to the lamp terminals in the usual manner. When it is desired to swing the lamp socket, this can be done very readily by merely turning it about the pivoted point since the support for the socket is very rigidly and securely attached to the cap 2.

Changes and modifications can be made

without departing from the spirit or scope of the invention.

I claim:

1. In an electric fixture, a shell and cap, said cap having a central opening, and a U-shaped support, the central portion of said support being pressed into said opening. 55
2. In an electric fixture, a shell and cap, said cap having a central opening, and a U-shaped support, the central portion of said support being pressed into said opening and riveted along the inside of said cap. 60
3. In an electric fixture, a shell and cap, said cap having a central opening, and a U-shaped support, the legs of said support being 65 provided with openings near the outer ends thereof, a portion of said support being pressed into said opening.
